UNITED STATES PATENT OFFICE.

SAMUEL J. TODD, OF HIGHLAND PARK, MICHIGAN, ASSIGNOR OF THREE-FOURTHS
TO BEN C. HUGHES, OF DETROIT, MICHIGAN.

PRIMING DEVICE FOR EXPLOSIVE-ENGINES.

1,168,920.

Specification of Letters Patent.

Patented Jan. 18, 1916.

Application filed November 30, 1914. Serial No. 874,649.

To all whom it may concern:

Be it known that I, SAMUEL J. TODD, a citizen of the United States of America, residing at Highland Park, in the county of Wayne and State of Michigan, have invented certain new and useful Improvements in Priming Devices for Explosive-Engines, of which the following is a specification, reference being had therein to the accompanying drawings.

This invention relates to a priming device for explosive engines, and more particularly to a device that can be advantageously used in connection with the multi-cylinder explosive engines of automobiles.

The primary object of my invention is to combine a spark plug and priming device and furnish the same with a fuel or gasolene supply that can be easily controlled by the operator of an automobile to insure positive and certain sparking at the proper time.

Another object of this invention is to furnish the cylinder of an engine with combined spark plugs and priming devices that can be actuated in synchronism to admit predetermined quantities of fuel or gasolene to the cylinders of the engine, thereby insuring an explosion in one of the cylinders of the engine for starting purposes.

A further object of my invention is to provide a simple, durable and inexpensive priming device, wherein the heat of a sparking plug is utilized for raising the temperature of gasolene or other fuel prior to the same being admitted to an engine cylinder for priming purposes.

With the above and other objects in view, the invention resides in the novel construction, combination and arrangement of parts to be hereinafter specifically described and then claimed.

Reference will now be had to the drawing, wherein—

Figure 1 is a diagrammatic view illustrating the fuel supply and operating mechanism for a priming device in accordance with my invention; Fig. 2 is a vertical sectional view of a combined spark plug and priming device that has been especially designed for Ford automobiles; and Fig. 3 is a horizontal sectional view of a portion of the same taken on the line x—x of Fig. 2.

In describing my invention by aid of the views above referred to, I desire to point out that I intend the same as merely illustrative

of an example whereby my invention may be applied in practice, and I do not care to limit my invention to the precise construction and arrangement of parts shown. The following description is therefore to be broadly construed as including substitute constructions and arrangement of parts that are the obvious equivalents of those to be hereinafter referred to.

Referring first to Figs. 2 and 3 of the drawing, 1 denotes a spark plug body made of metal with the lower end thereof reduced and exteriorly screwthreaded, whereby the spark plug body can be mounted in or connected to the wall 3 of an engine cylinder.

The spark plug body 1 has a stepped bore 4 throughout its length providing an annular shoulder 5 intermediate the edges thereof and a tapering seat 6 in proximity to the upper end of the spark plug body. The annular shoulder 5 affords a seat for a cushioning ring 7 supporting the collar 8 of a porcelain insulator body 9. The cushioning ring 7 is preferably made of copper and asbestos in the usual and well known manner and avoids fracture of the porcelain body 9 due either to sudden changes in the temperature, unequal expansion and contraction, and mechanical stress on the porcelain body caused by the clamping or securing means thereof. The lower end of the porcelain body 9 terminates in the lower end of the body 4 and is provided with a central electrode 10 coöperating with an electrode 11 of the spark plug body in forming a gap. The spark is formed in the well known manner by the jumping of the current from one electrode to the other, thereby firing the charge in an engine cylinder.

The upper end of the porcelain body 9 protrudes some distance above the spark plug body to avoid short circuiting. The central electrode 10, which is baked or otherwise mounted centrally of the porcelain body 9, protrudes from the upper end thereof and is provided with a binding post 12 to which a wire or electric conduit can be connected.

The seat 6 of the spark plug body 1 is provided with a liner 13 having diametrically opposed openings 14 registering with openings 15 in the outer wall of an annular reservoir or hollow collar 16 placed in the liner around the porcelain body 9. The hollow collar 16 serves as an auxiliary

reservoir and the inner annular wall thereof of practically contacts with the porcelain body 9, which is capable of retaining heat. The auxiliary reservoir is retained in the liner 6 by a nut 17 screwed in the upper end of the bore 4. The hexagonal portion 18 of the nut provides a bearing for a horizontally disposed pinion or circular rack 19 loosely held upon the upper end of the nut 17 by a retaining member 20 screwed or otherwise mounted upon the upper reduced end of the nut 17.

The spark plug body 1 has a longitudinal offset enlargement 21 provided with a tapering longitudinal bore 22 for a valve plug 23. The valve plug 23 is rotatable in the bore 22 and is retained therein by a nut 24 or other fastening means at the lower end of the valve plug. The upper end of the valve plug is reduced and machined to provide a small pinion 25 that meshes with the large pinion 19 and said large pinion has a radially disposed crank 26 to facilitate rotating the pinions 19 and 25 whereby movement is imparted to the valve plug 23. This plug has a chamber 27 adapted to hold a predetermined quantity of gasoline or other fuel, which is admitted to said chamber through the medium of an opening 28 at the upper end of the chamber, said opening registering with a port 29 in the enlargement 21 to establish communication between the auxiliary reservoir 16 and the chamber 27 when the plug 23 is adjusted for such purpose.

The valve plug 23 intersects an angularly disposed port 30 in the spark plug body 1 and the enlargement 21 thereof. The inner end of the port 30 communicates with the bore 4 and the outer end of said port is closed by a detachable plug 31. The lower end of the valve plug 23 has an opening 32 in communication with the lower end of the chamber 27 and said opening is adapted to register with the port 30 and thereby establish communication between the bore 4 and the chamber 27. The openings 28 and 32 of the valve plug 23 alternately register with the ports 29 and 30 and the openings 28 and 32 are alternately closed by walls of the bore 22. The wall of the spark plug body 1, opposite the enlargement 21, is provided with a port 33 registering with openings 14 and 15 in the liner 6 and the outer wall of the reservoir 16. The port 33 receives the end of a branch tube or pipe 35, and by referring to Fig. 1, it will be observed that the branch tubes or pipes of all the priming devices are connected to a main fuel or gasoline supply pipe 36. This supply pipe is connected to a main reservoir 37, within the engine hood and upon the dashboard 38 or a part thereof. The dashboard 38 is provided with a pivoted operating lever 39 connected by a reach rod 40 to all of the cranks 26, the connection be-

tween the reach rod 40 and the cranks 26 being such that either of the cranks can be released when it is desired to remove spark plug bodies from an engine cylinder.

It is possible, however, to adjust the spark plug body 1 and the nut 17 without disturbing the crank connection with the reach rod 40, as the large pinion or circular rack 19 is loose upon the nut and is simply employed for imparting movement to the valve plug 23. With the main fuel reservoir 37 within the hood of the automobile engine, said reservoir is heated to a certain degree, which is also true of the contents of the main supply pipe 36. The fuel or gasoline within the auxiliary reservoir 16 is further heated by reason of the porcelain body 9 extending through the central part of the auxiliary reservoir. It is therefore apparent that the gasoline or fuel is placed in a condition conducive to a perfect combustion when ignited by the ignition system of an engine.

When it is desired to prime an engine, it is only necessary for the operator of an automobile to pull upon the lever 39 and movement is imparted to all of the valve plugs 23 to shut off communication with the auxiliary reservoir 16 and establish communication between the chambers 27 and the bores 4 of the spark plug. Predetermined quantities of preheated fuel or gasoline will therefore be delivered at or in proximity to the electrodes of the spark plug, and as all the cylinders are simultaneously primed, it is apparent that with the ignition system in operation there is bound to be an explosion in one of the cylinders for starting the engine.

I attach considerable importance to the fact that the gasoline or fuel used for priming purposes is heated by the spark plug prior to being ignited thereby, and that measured quantities of gasoline or fuel are admitted to a cylinder for priming purposes, thereby reducing to a minimum the accumulation of carbon on or about the electrodes of the spark plug.

By using the term porcelain in connection with the body 8, it is meant to include not only porcelain itself, but also glass and any similar fragile homogeneous material suitable for insulation purposes of this character. Also, in using the terms "vertical" and "lateral", which are applicable in describing spark plugs that are vertically disposed, it is to be understood that the principle of my invention, as herein disclosed, is applicable to spark plugs in positions other than that of being upright relative to a cylinder wall.

What I claim is:

1. In a priming device for explosive engines, a spark plug, a valve body carried thereby, a fuel supply normally in communication with said valve body, an auxiliary

reservoir interposed between said valve body and said fuel supply and adapted to be heated by said spark plug, and means in said valve body for delivering predetermined quantities of heated fuel to said spark plug.

2. In a combined spark plug and priming device, a spark plug body, a valve body carried thereby, a porcelain body in said spark plug body, an auxiliary fuel reservoir in said spark plug body around said porcelain body, and a valve plug in said valve body adapted to establish communication between said auxiliary fuel reservoir and said spark plug body.

3. In a combined spark plug and priming

device, a spark plug body, a valve body carried hereby, a porcelain body in said spark plug body, an auxiliary fuel reservoir in said spark plug body around said porcelain body, 20 a valve plug in said valve body adapted to establish communication between said auxiliary fuel reservoir and said spark plug body and means supported by said spark plug for imparting movement to said valve 25 plug

In testimony whereof I affix my signature in presence of two witnesses.

SAMUEL J. TODD.
